UNITED STATES PATENT OFFICE.

SWEN R. SWENSON, OF SOUTH ORANGE, NEW JERSEY, ASSIGNOR TO MULTIPLE ELECTRIC PRODUCTS COMPANY, INC., OF NEW YORK, N. Y., A CORPORATION OF NEW YORK.

SOUND-REPRODUCING DEVICE AND ADJUSTING MEANS THEREFOR.

Application filed August 26, 1924. Serial No. 734,213.

This invention relates to devices for translating electric undulations into sound vibrations. More specifically it relates to electro-magnetic receivers of the diaphragm type 5 and has for one of its objects to increase the efficiency of operation of such devices.

Another object is to provide means for effectively and conveniently adjusting the diaphragm or diaphragms of a loud speaker.

10 Other objects and advantages will appear as the invention is hereinafter disclosed.

Referring to the drawings which illustrate what I now consider a preferred form of the invention:

15 Fig. 1 is a side elevation of a loud speaker embodying the features of my invention.

Fig. 2 is an enlarged sectional elevation of the device shown in Fig. 1 with the horn 20 broken away.

Fig. 3 is an enlarged elevation, partly in section, of the device shown in Figs. 1 and 2.

Fig. 4 is an inverted detail plan view showing a part of the adjusting mechanism.

25 While the features of invention may be applied to other receivers, such as head phones, and employed for other purposes, they are particularly applicable to devices now known in the art as loud speakers and 30 adapted to be employed in the reception of radio telephone signals. Therefore, I have selected for the purpose of illustration a loud speaker, in order to disclose the features of invention. A form of loud speaker now 35 preferred is illustrated in the drawings and may be constructed as follows:

The loud speaker comprises a casing 10 provided with a cap 11, which cap and casing enclose the diaphragm or diaphragms 40 and the electromagnetic means for actuating the same. It will be noted that the casing 10 is provided with a flange 12, the peripheral edge of this flange being screw threaded at 13 to cooperate with threads provided on 45 the inner wall of the cap 11, whereby the cap and casing may be detached from each other and whereby relative rotation of the cap and cover causes relative longitudinal movement of said cap and cover.

50 The loud speaker comprises also a base 14 upon which the device is adapted to rest, the cap 11 being suitably secured to the base as by means of cooperating screw threads 15 provided on the exterior wall of the cap and

inner wall of the base. The cap 11 is provided with a central opening 16 into which the metallic ferrule 17 of amplifying horn 19 extends. Preferably the ferrule 17 is externally threaded at 18 to screw into the opening 16, the wall of the latter being 55 tapped for that purpose. The horn 19 is preferably constructed of molded wood pulp, although other materials may satisfactorily be employed.

It will now be appreciated that the cap 60 11 supports the horn 19 above it and the casing 10 below it, and is in turn supported by the base section 14. I shall now proceed to describe the instrumentalities for translating the electric undulations into sound vibrations, all of these instrumentalities being located within the container formed by the casing 10 and cap 11.

70 The electromagnets 20, 20 (of which one of the pairs is shown in Fig. 2) and permanent polarizing magnet 21 common to devices of this general type and, except for changes in dimensions, to watch-case telephone receivers, are mounted within the casing 10 and suitably secured therein. Any suitable means (not shown) may be employed 75 for supplying the undulating current to the windings of the electromagnets 20, 20. A diaphragm 22 of silicon steel, iron or other suitable material is mounted across the open 80 upper end of the casing 10 and is adapted to be vibrated by undulating currents in the electromagnets. A second diaphragm 23 is mounted in the cap 11 between the annular shoulder 24 of the latter and the diaphragm 85 22. Preferably an annular gasket 25 of rubber strip, or other suitable compressible material, is interposed between the shoulder 24 and the upper outer edge portion of the diaphragm 23. The diaphragms are spaced 90 apart at their centers by a sleeve 26 of hard rubber or other suitable material, the diaphragm 22 having a struck-up teat 27 which extends into the sleeve 26 and the latter being 95 preferably shellacked or otherwise secured to the brass washer 28 riveted to the diaphragm 23 at the center thereof. It will be noted that the diaphragms 22 and 23 are 100 of different diameters (the latter being the larger) so that the natural period of one diaphragm differs from that of the other. By virtue of this construction more faithful 105 reproduction of sound is obtained. The

faithfulness of reproduction may be still further increased by making the diaphragm 23 of micarta, impregnated fabric, or other suitable non-metallic material, the diaphragm 22 being constructed of magnetizable metal.

In the use of the instrument, the cap 11 and casing 10 are screwed relatively toward each other, thereby causing the circular disc-shaped diaphragms 22, 23 to bulge or convex away from each other at their central portions, the peripheries of the diaphragms being moved relatively toward each other. Obviously, relative movement of the cap and casing toward each other not only increases the convexity of the diaphragms but also moves the diaphragm 22 nearer the pole tips of the electromagnets 20, 20. Conversely, relative movement of the cap and casing away from each other decreases the convexity of the diaphragms and permits the diaphragm 22 to move away from the pole tips. Bearing in mind that certain transmitting stations are stronger than others, that some are located more remotely than others, and that other factors vary the desirability, if not the necessity, of adjustment, and convenient adjustment of the diaphragm or diaphragms will be appreciated. A preferred form of adjusting means is shown in the drawings and may be constructed as follows:

The under side of the flange 12 of the casing 10 has secured thereto a circular rack or spur gear 30 adapted to mesh with a pinion 31 provided with a square central opening adapted to receive the squared portion 32 of a shaft 33, journaled for rotation in a suitable opening in the upper part of the base 14. The pinion 31 is held on its shaft by means of a screw 36, a washer 37 being mounted between the pinion 31 and the head of the screw. The shaft 33 is provided with an enlarged portion 34 which, together with the pinion 31, limits the endwise movement of the shaft. A milled head 35 facilitates manual rotation of the shaft 33 and its pinion 31.

When the device is assembled at the factory the casing 10 and cap 11 are rotated with respect to each other until the best average adjustment of the diaphragm is obtained. The cap 11 is also screwed tightly into the base 14 and, if desirable, cemented thereto by applying any suitable cement to the screw threads 15 before the cap is screwed home into the base. The pinion 31 is then mounted as shown in Fig. 2. The user may now adjust the diaphragms simply by turning the knob 35 in the desired direction and to the desired extent. Obviously, rotation of the knob 35 causes rotation of the pinion 31, the gear 30, and the casing 10, the cap 11 remaining stationary with respect to the base 14. In view of the fact that the gear 31 is much smaller than the gear 30, fine

adjustments may be effected and inadvertent turning of the casing 10 is prevented.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means.

What I claim is:—

1. A loud speaker comprising in combination, a casing and cap therefor, an electromagnet mounted within said casing, a pair of diaphragms spaced at their centers and mounted between said electromagnet and cap, means for causing said diaphragms to convex away from each other upon relative rotation of said cap and casing in a predetermined direction, a base to which said cap is secured and surrounding said casing, and means operable from the exterior of said base for causing relative rotation of said casing and base.

2. The combination set forth in claim 1, in which the last mentioned means comprises a gear secured to said casing.

3. The combination set forth in claim 1, in which the last mentioned means comprises a circular rack secured to said casing, and an adjusting pinion of smaller radius meshing with said rack.

4. The combination set forth in claim 1, in which the last mentioned means comprises a circular rack secured to said casing, an adjusting pinion of smaller radius meshing with said rack, and a shaft for turning said pinion and extending through said base.

5. A device for translating electrical undulations into sound vibrations and comprising in combination, a two-part casing, an electromagnet and diaphragm mounted within said casing, means for causing relative movement of said electromagnet and diaphragm toward and away from each other upon relative rotation of the two parts of said casing, and means comprising a gear wheel secured to one of the parts of said casing and a manually operable pinion meshing with said gear wheel for causing relative rotation of the parts of said casing.

6. A device for translating electrical undulations into sound vibrations and comprising in combination, a two-part casing, an electromagnet mounted within said casing, a pair of diaphragms spaced at their centers and mounted between said electromagnet and one of the parts of said casing, means for causing said diaphragms to convex away from each other upon relative rotation of the two parts of said casing in a predetermined direction, and means comprising a gear wheel secured to one of the

parts of said casing and a manually operable pinion meshing with said gear wheel for causing relative rotation of the parts of said casing.

5 7. The combination set forth in claim 1, in which the natural period of one diaphragm is greater than that of the other.

8. The combination set forth in claim 6, in which the natural period of one dia-
10 phragm is greater than that of the other.

9. A loud speaker comprising in combina-
15 tion, a casing and cap therefor, an electro-
magnet and diaphragm mounted within said
casing and cap and relatively movable toward
and away from each other upon relative ro-
tation of said casing and cap in opposite
20 directions, a base to which said cap is se-
cured and surrounding said casing, and
means operable from the exterior of said
base for causing relative rotation of said
casing and base, said last mentioned means
25 comprising a gear secured to said casing.

10. A loud speaker comprising in combi-
25 nation, a casing and cap therefor, an elec-
tromagnet and diaphragm mounted within
said casing and cap and relatively movable
toward and away from each other upon rela-
tive rotation of said casing and cap in op-
30 posite directions, a base to which said cap
is secured and surrounding said casing, and
means operable from the exterior of said
base for causing relative rotation of said
casing and base, said last mentioned means
35 comprising a circular rack secured to said

casing and an adjusting pinion of smaller
radius meshing with said rack.

11. A loud speaker comprising in combi-
nation, a casing and cap therefor, an electro-
magnet and diaphragm mounted within said
casing and cap and relatively movable to-
ward and away from each other upon rela-
tive rotation of said casing and cap in oppo-
site directions, a base to which said cap is
40 secured and surrounding said casing, and
means operable from the exterior of said
base for causing relative rotation of said
casing and base, said last mentioned means
45 comprising a circular rack secured to said
casing, an adjusting pinion of smaller ra-
dius meshing with said rack, and a shaft
50 for turning said pinion and extending
through said base.

12. A loud speaker comprising in combi-
nation, a casing and cap therefor, an electro-
magnet and diaphragm mounted within said
casing and cap and relatively movable to-
ward and away from each other upon rela-
tive rotation of said casing and cap in in
55 opposite directions, a base to which said cap
is secured and surrounding said casing, said
base being adapted to rest at its bottom on
a flat supporting surface, and means includ-
ing a part extending upwardly through the
60 top of said base and operable from the ex-
terior of said base for causing relative ro-
tation of said casing and base.

In testimony whereof I hereto affix my
signature.

SWEN R. SWENSON.
